UNITED STATES PATENT OFFICE.

FERDINAND J. HAGEN AND LUDWIG WIELAND, OF NEW YORK, N. Y.,
ASSIGNORS TO THE EUREKA CIGAR MACHINE COMPANY, OF NEW
JERSEY.

CIGAR-BUNCHING MACHINE.

SPECIFICATION forming part of Letters Patent No. 460,278, dated September 29, 1891.

Application filed October 2, 1890. Serial No. 366,855. (No model.)

To all whom it may concern:

Be it known that we, FERDINAND J. HAGEN and LUDWIG WIELAND, both citizens of the United States, residing in the city, county, and State of New York, have invented a new and useful Improvement in Cigar-Bunching Machines, of which the following is a specification.

This invention relates to the feeding mechanism of cigar-bunching machines, more particularly those in which the tobacco is fed from a supply-hopper through a throat into a bunch-mold by a feed-block working in the throat, and when said mold is packed and the tobacco therein separated from the remainder, as by a knife, the bunch in the mold is carried to a rolling and binding mechanism. An example of these machines is shown and described in United States Letters Patent No. 415,943, issued to the said Ferdinand J. Hagen, on the 26th day of November, 1889, to which patent reference is made herein.

The main object of our improvement is to render the reciprocating feed-block so compensating that the different lateral portions of the feed-block will yield elastically, according to the resistance offered thereto by the tobacco in the corresponding parts of the mold as the tobacco is packed therein, and to provide for regulating the degree of pressure at which the various portions of the feed-block will yield, so that the tobacco will be packed uniformly in all parts of the mold and a cigar of uniform density thus produced.

A further object of the invention is to provide for the automatic regulation of the flow of tobacco to the compensating feed-block by the yielding of the same to an excess of tobacco in front thereof.

The invention consists of certain novel features of construction and combinations of parts by which the above ends are attained; and in order that the invention may be clearly understood we shall first describe in detail the mode in which it is carried into effect, and then point out its several features in the claims.

Reference is to be had to the accompanying drawings, forming a part of this specification, in which—

Figure 1 is a sectional side elevation illustrating a feeding mechanism embodying our invention applied to a cigar-bunching machine which is in other respects similar to that described in the patent of Hagen referred to. Fig. 2 is a sectional plan view on the line X X, Fig. 1. Fig. 3 is a cross-sectional elevation on the line Y Y, Fig. 1. Figs. 4 and 5 are detail views.

Like letters of reference designate corresponding parts in the several figures.

A' designates the frame-work of the machine; A, the hopper in which the loose filler is contained; B, the rag-wheel by which the filler in the hopper is kept in motion; C, the throat to which the filler passes by the wheel B; D, the opening in the top plate of the throat C; E, the feed-block vibrating inward and outward and reciprocating longitudinally in said opening D; F, the mold, which is in this instance solid and which oscillates from the mouth of the throat C to the rolling mechanism, (not shown;) F', the knife by which the tobacco in the mold is separated from the remainder, and G the gang of cams by which the desired motions of the feed-block and mold are obtained, all of which parts serve the principal functions ascribed to them in Hagen's patent referred to.

To make the different lateral portions of the feed-block yield independently of each other according to the respective resistances which they meet from the packing of the filler in the mold F, which is preferably cigar-shaped, like that described in the said patent of Hagen, we construct the feed-block of a plurality of—in this case three—longitudinal sections E' and mount them to slide lengthwise independently of each other in a guide-block carrier H. The carrier H has side plates H' on opposite sides of the feed-block, between which side plates the sections E' are held from vertical movement on the carrier, while allowed their longitudinal compensating feeding movement thereon by a transverse guide-plate J, rigidly connecting the side plates H' and extending through coincident longitudinal slots K in the several sections E'. Each block-section E' is provided on its forward end with an upwardly-extending lug E², to which we pivot to allow vertical play a longitudinal guide-bar O, and we pass the rear

- ends of the several corresponding guide-bars O loosely through a transverse guide M', which is fixed to the hanging arm M² of an angle-lever M, the other arm of which follows 5 a cam, substantially as in Hagen's patent aforesaid, and gives the longitudinal feeding motion to the feed-block-carrying guide M'. On each guide-bar O, between said guide M' and the respective lug E², we place a coiled 10 spring L and a screw-nut O' for adjusting the tension of the spring, and on the end of each guide-bar O, back of the guide M', screw a collar-nut O², having a convex bearing against said guide M', so that as said guide M' is reciprocated longitudinally, as before stated, the several block-sections will be likewise reciprocated simultaneously, while an increase 15 in resistance to any section over the others will cause the said section to be retracted, 20 relatively to the others, the respective spring L yielding to permit said retraction. By the tension-adjusting nut O' on each guide-bar O the proper yielding point of each section can be regulated to a nicety.
- 25 The side plates H' of the feed-block carrier H are provided with rigid arms P, which are in this case pivoted to lugs Q' on the top of the throat frame-work, so that the carrier H can vibrate and with it the sectional feed-block 30 E upward at the end of the forward feeding movement of the said feed-block and downward at the end of the rearward movement of the feed-block. Said vibrating motion is here given to the carrier and feed-block by 35 links R, connecting the side plates H' of the carrier with the slotted arms S' of an angle-lever S, which is fulcrumed at its angle to the frame-work of the machine and has its other arm engaged with a cam, substantially as described in Hagen's patent before mentioned.
- 40 To automatically check the flow of tobacco from the hopper when there is an excess of tobacco in front of the feed-block, which will cause the same to be unduly retracted, we arrange 45 a hanging cut-off T in an opening in the front of the hopper A and in line with the feed-block, so that the retraction of the same will cause it to press the cut-off T into the hopper toward the feed-wheel, and thus check 50 the flow of tobacco therethrough. The cut-off T will swing back by gravity when the pressure on the feed-block is relieved.
- 55 The shaft of the feed-wheel B is mounted to revolve in adjustable bearings U, (shown in Fig. 5,) pivoted to the sides of the hopper A and arranged to be secured in position when adjusted by ordinary set-screws (not shown) passing through the slots V.
- 60 We claim as our invention—
- 65 1. In a cigar-bunching machine, the combination, with the mold, the feed-throat, the feed-block, and the feed-block-operating mechanism, of an elastic connection between the feed-block and its operating mechanism, substantially as described.
- 70 2. In a cigar-bunching machine, the combination, with the mold and the feed-throat, of a sectional feed-block, feed-block-operating mechanism, and means for adjusting the feed-block sections relatively to each other, substantially as described.

75 3. In a cigar-bunching machine, the combination, with the mold and the feed-throat, of a sectional feed-block, feed-block-operating mechanism, and independent elastic connections between each feed-block section and its operating mechanism, substantially as described.

80 4. In a cigar-bunching machine, the combination, with the mold, the feed-throat, the feed-block, and the feed-block-operating mechanism, of an elastic connection between the feed-block and its operating mechanism, and means for adjusting the tension of said elastic connection, substantially as described.

85 5. In a cigar-bunching machine, the combination, with the mold, the feed-throat, and the feed-block, of a carrier in which the feed-block is mounted to slide, but cannot turn, means for vibrating the carrier, together with the feed-block, inward and outward, and means for reciprocating the feed-block longitudinally, substantially as described.

90 6. In a cigar-bunching machine, a tobacco-feeder comprising a sectional feed-block, a carrier on which the feed-block sections are independently movable in the direction of the feed, and means for limiting the movement of the separate feed-block sections relative to the carrier, substantially as hereinbefore set forth.

95 7. In a cigar-bunching machine, the combination, with a mold and feed-throat, of an inwardly and outwardly vibrating feed-block carrier, a plurality of longitudinally-working feed-block sections on said carrier, longitudinal guide-bars pivoted to the respective feed-block sections, a longitudinally-reciprocating guide on which the several guide-bars work, and elastic connections between the said guide-bars and the said reciprocating guide, substantially as described.

100 8. In a cigar-bunching machine, the combination of a plurality of feed-block sections, guide-bars connected thereto, a longitudinally-reciprocating guide on which said guide-bars work, springs between the guide-bars and said reciprocating guide, and spring-tension-adjusting nuts on said guide-bars, substantially as described.

105 9. In a cigar-bunching machine, the combination, with the hopper, the feed-throat, the mold, the feed-block, and feed-block-operating mechanism to which the feed-block is yieldingly connected, of a hopper-supply cut-off operated by an undue yielding of the feed-block, substantially as described.
